(57) **CLAIM**

The ornamental design for a cleavage-enhancing garment insert, as shown and described.

DESCRIPTION

FIG. 1 is a front elevation view of the cleavage-enhancing garment insert inside of a bra;

FIG. 2 is a front elevation view of the cleavage-enhancing garment insert;

FIG. 3 is a rear elevation view of the cleavage-enhancing garment insert;

FIG. 4 is a left side elevation view of the cleavage-enhancing garment insert;

FIG. 5 is a right side elevation view of the cleavage-enhancing garment insert;

FIG. 6 is a top plan view of the cleavage-enhancing garment insert; and,

FIG. 7 is a bottom plan view of the cleavage-enhancing garment insert.

The broken lines are for illustrating portions of the article that form no part of the claimed design.
